J. H. SCHMITZ

NUT OR BOLT HOLDER

Filed Apr. 7, 1922

J.H. Schmitz Inventor

By *Cadmon & Co.*
Attorney

UNITED STATES PATENT OFFICE.

JOSEPH H. SCHMITZ, OF SOUTHMAYDE, TEXAS.

NUT OR BOLT HOLDER.

Application filed April 7, 1922. Serial No. 550,398.

To all whom it may concern:

Be it known that I, JOSEPH H. SCHMITZ, a citizen of the United States, residing at Southmayde, in the county of Grayson and State of Texas, have invented a new and useful Nut or Bolt Holder, of which the following is a specification.

This invention aims to provide a simple means for holding nuts, bolts and the like, in inaccessible places, the tool being of peculiar utility in the hands of automobile mechanics and others who are called upon to work in a limited space.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the drawings:—

Figure 1 shows in side elevation, a tool constructed in accordance with the invention; Figure 2 is an elevation wherein the tool is viewed edgewise; Figure 3 is a fragmental side elevation showing a modification.

In carrying out the invention, there is provided a main member 1 including a shank 2 provided with a laterally projecting jaw 3, the shank 2 having a handle 4 offset in a direction opposite to that in which the jaw 3 projects.

The tool comprises an auxiliary member 5 including a jaw 6 disposed parallel to the jaw 3 and located outwardly thereof, the auxiliary member 5 embodying an extension 7 disposed at an angle to the shank 2 and provided with a slot 8.

The numeral 9 marks a lever including a handle 10 disposed parallel to the handle 4 of the main member 1, the lever 9 comprising a curved head 11 projecting beyond the

shank 2 in the same direction in which the handle 10 projects, the head 11 having a stud or other projection, denoted by the numeral 12 and mounted to slide in the slot 8 of the part 7 of the auxiliary member 5. A pivot element 14 connects the intermediate portion of the head 11 on the lever 9 with the shank 2 of the main member 1.

The main member 1 carries a pivot element 15 received in a slot 16 in the auxiliary member 5, the ordinary shifting construction, common in pliers, being afforded by the slot 16.

The inner faces of the jaws 6 and 3 are provided with longitudinal recesses 17, there being transverse ribs 18 on the inner faces of the jaws, the ribs being located on opposite sides of the recesses 17. The jaws 6 and 3 may be supplied with transverse recesses 19, the various recesses in the jaws facilitating the holding of work of different kinds.

When the handles 4 and 10 are pressed together, the boss 12 rides in the slot 8, the auxiliary member 5 tilts on its fulcrum 15, and the jaw 6 cooperates with the jaw 3.

In the modification shown in Figure 3, parts hereinbefore described have been designated by numerals previously used, with the suffix "a."

The pivot element 15^a for the auxiliary member 5^a is spaced from the jaw 3^a, and the jaw 6^a is located inwardly of the jaw 3^a, instead of outwardly of that jaw, as shown in Figure 1. The position of the handles 10^a and 4^a is reversed from the showing of Figure 1, in order that, when the handles 4^a and 10^a are pressed together, the jaw 6^a may cooperate with the jaw 3^a.

Having thus described the invention, what is claimed is:

In a device of the class described, a main member including a shank provided at one end with a laterally offset handle, the shank being provided at its opposite end with a jaw, projecting in a direction opposite to that in which the handle is offset; a lever fulcrumed intermediate its ends on the shank and provided with a handle disposed approximately parallel to the handle of the 100

shank; and an auxiliary member fulcrumed intermediate its ends on the shank, the auxiliary member comprising a jaw cooperating with the jaw of the shank, and comprising
5 an extension having a slot, and a lever having a projection received slidably in the slot.
In testimony that I claim the foregoing

as my own, I have hereto affixed my signature in the presence of two witnesses.

JOSEPH H. SCHMITZ.
